UNITED STATES PATENT OFFICE.

JOAN CHAPMAN, OF NEW YORK, N. Y.

DESIGN FOR A DOLL.

Application filed September 22, 1925. Serial No. 14,853. Term of patent 3½ years.

To all whom it may concern:

Be it known that I, JOAN CHAPMAN, a citizen of the United States, residing at New York, borough of Manhattan, in the county and State of New York, have invented a new, original, and ornamental Design for Doll, of which the following is a specification, reference being had to the accompanying drawings, forming part thereof.

In the drawings—

I claim:

The ornamental design for a doll, as shown.

JOAN CHAPMAN.
